N° 1,038.

Design for Plates of a Cooking-Stove,
by N. S. Yudder, of Troy, N.Y.

Patented Aug. 10, 1858.

Res. 1038

N. S. Vedder, of Troy, N. Y.
Letters Patent No. 1038, dated Aug. 10, 1858,

The schedule referred to in the Letters Patent and making part of the same.

To all whom it may concern:

Be it known that I, N. S. Vedder, of the City of Troy, in the County of Rensselaer, and State of New York, have invented or produced a new and original Ornamental Design for Plates of a Cooking Stove; and I do hereby declare that the following is a full and exact description of the same, reference being had to the annexed photographic drawing, making a part of this Specification.

My ornamental design for Cooking Stove plates consists of a rosette *a*, check work *b*, scroll work *c*, and moldinged, formed and disposed upon the large oven door *A*, small oven door *B*, and the door or panel *C*, at the end of the fire box, substantially as represented in the annexed photograph; and the ornamental work *E*, and moldings *F*, formed and arranged upon the side-plate *D*, as shown in the said drawing. -

What I claim as my invention or production and desire to secure by Letters Patent is the ornamental design herein described and represented in the annexed photographic drawing, for the plates *A*, *B*, *C* and *D*, of a Cooking Stove.

Witnesses.
